UNITED STATES PATENT OFFICE

2,372,003

SECTIONAL LADDER

Raymond A. Kennedy, Sioux City, Iowa

Application July 21, 1943, Serial No. 495,637

1 Claim. (Cl. 304—10)

This invention relates to ladders, and more particularly to a sectional multi-use ladder.

An object of this invention is to provide a sectional ladder wherein the adjacent ends of the sections are interlocked together so that a firm ladder assembly will be provided.

Another object of this invention is to provide a sectional ladder which is so constructed that the sections may be arranged in a number of ways. For instance, in one arrangement the sections may be interlocked to provide a straight ladder. In another instance the sections may be connected together in pairs and disposed in upwardly convergent relation so as to form a high stepladder. In a further instance a low firm stepladder may be formed by using one section as a base and mounting two upwardly convergent sections on the base. Additional arrangements may also be formed which will be readily apparent to the user.

With the foregoing objects in view, and others which may hereinafter more fully appear, the invention consists of the novel construction, combination and arrangement of parts, as will be more specifically described, and illustrated in the accompanying drawings wherein are shown embodiments of the invention, but it is to be understood that changes, variations and modifications may be resorted to which fall within the scope of the invention as claimed.

In the drawings:

Figure 1 is a detail front elevation partly broken away of a sectional ladder constructed according to an embodiment of this invention.

Figure 2 is an enlarged fragmentary front elevation partly in section showing the connection between the adjacent sections.

Figure 3 is a sectional view taken on the line 3—3 of Figure 2.

Figure 4 is a detail side elevation of another arrangement of the ladder sections.

Figure 5 is a fragmentary front elevation partly in section of the upper portion of the ladder section shown in Figure 4.

Figure 6 is a fragmentary front elevation partly in section and showing in exploded form the manner of connecting the adjacent ladder sections together.

Figure 7 is a fragmentary side elevation, partly in section, of one of the ladder rails.

Figure 8 is a side elevation of a number of ladder sections arranged as a stair scaffold.

Figure 9 is a front elevation of a number of ladder sections arranged as an indoor scaffold or shelf support.

Figure 10 is a fragmentary sectional view taken on the line 10—10 of Figure 9, and

Figure 11 is a fragmentary vertical section of a number of ladder sections arranged as an outdoor scaffold.

Referring to the drawings, the numerals 10 and 11 designate a pair of ladder sections constructed according to an embodiment of this invention, which are interlocked together in Figure 1 to form 10 a straight ladder. As many sections as may be desired may be interlocked together to form the desired length of ladder.

The ladder section 10 is formed of a pair of side rails 12 and 13, and a plurality of rungs 14 are 15 connected between the rails 12 and 13. The rungs 14 are arranged so that the end rungs will be spaced inwardly from the opposite ends of the section. The side rails 12 and 13 are alike in construction and may be formed out of wood or 20 other suitable material. The rails, at each end thereof, are formed with outwardly opening notches 15 and 16 and where the rails are formed out of wood they are reinforced against splitting by means of transversely extending rivets or bolts 25 17 and 18, respectively. The bolts 17 and 18 are disposed at a point spaced inwardly from the inner ends of the notches 15 and 16.

The ladder section 11 is formed of a pair of parallel side rails 19 and 20, which have secured 30 therebetween rungs 21. The rungs 21 are intermediate rungs and opposite end rungs 22 and 23 are secured transversely between the rails 19 and 20 at a point inwardly from the opposite ends of the rail. The rung 22 has projecting opposite 35 end portions 24 which project beyond the outer sides of the rails 19 and 20, and the rung 23 has projecting opposite end portions 25 which project beyond the opposite sides of the rails 19 and 20. The projecting end portions 25 are adapted to 40 seat in the notches 15 or 16 of the ladder sections 10, and the rails 19 and 20 are also formed with notches 26 at the opposite ends thereof whereby the rails 19 and 20 may interlock with an adjacent rung 14 of the ladder section 10. The two 45 ladder sections 10 and 11 are firmly locked together against endwise movement by means of resilient hooks 27 which are pivotally mounted on a pivot member 28 carried by the rails 19 and 20. There are two hooks 27 at each end of the 50 ladder section 11 and the hooks are formed with reverted bills 29 to facilitate snapping of the hooks over a rung 14. The ladder section 11, at each end thereof, is formed with holes 30 through which a bolt 31 is adapted to engage when a pair 55 of ladder sections, as for instance, a pair of sec-

tions 11, are mounted in upwardly convergent relation as shown in Figure 4. At this time the two ladder sections have their lower ends mounted on the end rungs 14 of the ladder section 10 which constitutes a base section. The ladder section 10 may also be formed with holes 32 in the rails 12 and 13 adjacent the ends of these rails so that bolts 31 may be extended through the holes 32 and holes 30 of a section 11 when an extension step ladder is formed embodying a pair of interlocked sections 10 and 11 or other desired arrangement of sections.

When the ladder sections are arranged, as shown in Figure 4, the ladder section 10, which is the base section, prevents spreading of the pair of sections 11, at the lower ends of this latter section and thereby provides a firm foundation for the short step ladder.

In Figure 8 there is shown a further arrangement of the ladder sections wherein a stair ladder or scaffold is provided. Two sections 10 and 11 are connected together in alignment as hereinbefore described, and then a second section 10 is bolted as at 31a to the upper end of the upper section 11. The second section 10 is adapted to rest on an upper stair tread and this latter section is held against spreading relative to the aligned sections by means of a bracing hook 33 which engages adjacent rungs of the upper sections as shown.

Referring to Figures 9 and 10, there is shown a further arrangement of the ladder sections wherein the sections are arranged to form an indoor scaffold or shelf support. A number of sections 10 and 11 are connected together in alignment and a series of such connected sections are then disposed in a vertical position at right angles to a wall or other support 34. Nails or bolts 35 are extended through bolt holes 31 and 32 in sections 11 and 10, respectively, and engage with the wall 34. Shelf boards 36 may be mounted on the rungs of adjacent sections as shown in Figure 9, and where this arrangement is de-

signed as a shelf construction, the boards 36 may be engaged with all of the rungs of the ladder sections.

In Figure 11 there is disclosed an outdoor scaffold constructed from the ladder sections 10 and 11. A number of ladder sections 10 and 11 are disposed in alignment as hereinbefore described, and one section, such as a section 11, is disposed at right angles to the connected sections, being locked at its outer end on a section 10 by means of the hooks 21. The inner end of the horizontal section which is designated 11b is then mounted on a cleat or board 37 secured to the outer side of the building. A holding wire 38 is then extended through bolt holes 30 and wrapped around nails or bolts 39 mounted in the cleat 37. The supporting boards or platform may now be mounted on the horizontal sections 11b. The horizontal sections 11b constitute not only bracing members but also supporting members for the boards or platforms.

I claim:

A scaffold comprising upright ladder members formed of disconnectible ladder sections each having side rails and cross rungs, horizontal ladder sections having side rails and cross rungs, the side rails of the horizontal ladder sections having outer ends detachably engaged with cross rungs of the vertical ladder sections and their inner end portions formed with transverse openings spaced from their inner ends, a horizontal support extending transversely of the horizontal ladder sections and adapted to be mounted against a wall with inner ends of the horizontal ladder sections resting upon the horizontal support, anchors carried by and projecting upwardly from said support adjacent the horizontal ladder sections, and strands passing through said openings and extending towards said support and engaged about said anchors to hold the inner ends of the horizontal ladder sections upon said support.

RAYMOND A. KENNEDY.
